UNITED STATES PATENT OFFICE

WILLIAM W. LOWREY, OF NEW YORK, N. Y.

DESIGN FOR A GLASS STOPPER FOR BOTTLES.

SPECIFICATION forming part of Design No. 30,833, dated May 23, 1899.

Application filed April 24, 1899. Serial No. 714,323. Term of patent 3½ years.

To all whom it may concern:

Be it known that I, WILLIAM W. LOWREY, a citizen of the United States, residing at Stuyvesant Place, in the borough of Richmond, 5 city of New York, and State of New York, have invented and produced a new and original Design for Glass Stoppers for Bottles, of which the following is a specification, reference being had to the accompanying drawings, 10 forming part thereof.

Figure 1 represents a face view showing my new design. Fig. 2 is an edge view of the same. Fig. 3 is a transverse section taken on the line X X of Fig. 1.

15 As shown in the drawings, the leading or material feature of my design consists of forming the edge or contour of the head of the

stopper by two long curves A, terminating in abrupt curves B, whose scroll or convolute ends extend inwardly, all of which are separated from the plain C by the bevel D. The two upper abrupt curves B are separated by a palm or fan shaped ornament, the lower abrupt curves terminating in the shank E of the stopper.

Having described my invention, what I claim as new, and desire to secure by Letters Patent, is—

The design for a glass stopper for bottles as herein shown and described.

WILLIAM W. LOWREY.
